UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed February 9, 1924 Serial No. 691,577.

This invention relates to improvements in anti-friction bearings.

One object of this invention is to provide an anti-friction bearing particularly adapted for use as a side bearing on railway cars and wherein the anti-friction element is automatically centered under the influence of gravity after each actuation thereof when the pressure is released therefrom.

10 More specifically, an object of this invention is to provide a side bearing having pendulums or counterweights so arranged that when the anti-friction element is moved to either side of its normal central position, 15 the counterweights will be oscillated and thereby moved to a position of unstable equilibrium to automatically insure the return of the anti-friction element when the load is removed.

20 Other objects and advantages of the invention will more clearly appear from the description and claims hereinafter following.

In the drawing forming a part of this 25 specification, Figure 1 is a vertical sectional view taken through the ends of the body and truck bolsters of a car, showing my improvements in connection therewith. Figure 2 is a vertical sectional view taken substantially on the line 2—2 of Figure 1. And Figure 3 is a vertical sectional view showing a modified form of my device.

In said drawing, 10 denotes the under portion of the body bolster and 11 the upper 35 portion of the opposed truck bolster of a railway car. As shown, the improved side bearing is attached to the truck bolster and comprises, broadly, a retaining member or housing A; an anti-friction element B; and 40 a pair of pendulum or counterweights C—C.

In the form shown in Figures 1 and 2, the housing or retainer A is preferably in the form of a hollow box casting, open at its top and bottom, having end walls 12 and side 45 walls 13, the latter extended toward one another at their upper ends to provide top flanges 14. Lugs 15 are provided adjacent the bottom of the retaining member to receive rivets 16 whereby the housing may be 50 secured to the bolster 11.

A bearing block 17, preferably having a hardened wear plate 18, is secured in the bottom of the housing by peening portions 19 of the lower edges of the end walls 12 over the tapered ends of the bearing block 55

17 as shown in Figure 1. Openings 20 are provided through the bottom of the side walls of the housing, whereby dirt, cinders or other foreign matter may be removed from the bearing.

60 The anti-friction element proper B is shown as comprising a cylindrical roller of slightly less length than the distance between the opposed edges of the flanges 14, said roller being adapted to roll back and forth on the wear plate 18 and project above the housing, said roller also being provided with lugs or trunnions 25 projecting axially therefrom at the ends thereof.

65 The counterweights or pendulum members C—C are arranged, one at each end of the roller, each of said pendulum members comprising a substantially sector-shaped portion having a laterally extending lug or pin 21 integral therewith at the upper end thereof, 70 adapted to be pivotally received within an opening 22 through the side wall 13 of the housing. Each of the pendulum members is further provided with a substantially elliptical or oval recess or opening 23, said opening 75 extending substantially vertically when the pendulums are in normal position, this opening being extended downwardly to the lower end of the pendulum member at 24, the lower part of the same being only for the purpose of entering trunnions of the roller into slots 23 of the counterweights when assembling, and being only of sufficient width for 80 this purpose. It will be noted that the pivotal axes of the pendulum members are located above the rotational axis of the anti-friction roller and that the elliptical recesses have their major axes in vertical alignment with the axes of the pendulum members.

85 The operation of the device is as follows, 90 assuming that the anti-friction roller is actuated toward the left to the dotted line position shown. As soon as the roller moves toward the left, the trunnions will engage with the side walls of the elliptical openings 95 of the pendulum members, oscillating said members about their pivotal axes, to the dotted line position indicated, and in 100 which position said pendulum members will be in a state of unstable equilibrium. As soon as the actuating pressure is released, the pendulum members will pull the roller to its normal position.

105 The recesses 23 conform substantially closely to the shape generated by lines always 110

- normal to horizontal lines through the axes of the trunnions, during the pivotal movement of the pendulum, so that the pendulums exert a substantially horizontal pull 5 upon the trunnions of the roller during the entire returning movement, thus increasing the returning effect of the pendulum members and their efficiency for the purpose for which they were intended.
- 10 In the form shown in Figure 3, the housing A' has end walls 102 and side walls 103, the bottom of the housing being open to receive a bearing block 117 having a hardened wearing plate 118 adapted to coact with the 15 anti-friction element. The anti-friction roller B' is arranged to roll back and forth on the hardened wear plate 118 and is provided with longitudinally extending lugs 125 at the ends thereof.
- 20 The pendulum members or counterweights C' are arranged between the side walls of the housing and the ends of the anti-friction roller, each of said pendulum members having an opening 122 adjacent its upper 25 end, so that said members may be pivotally suspended on pins or lugs 121 carried by the housing. Each of the pendulum members is also provided with a substantially elliptical opening 123 adapted to receive the 30 cooperating lug 125 of the anti-friction element.

From the foregoing description, it will be seen that all the parts are held in their assembled relation in the manner hereinbefore described, with but a minimum amount of lateral and vertical shifting, and that automatic return of the anti-friction element to its normal central position is insured, all without the necessity of using springs or 40 other delicate means likely to get out of order.

I have herein shown and described what I now consider the preferred manner of carrying out my invention, but the same is merely illustrated and I contemplate all changes and modifications that come within the scope of the claims appended hereto.

I claim:

1. In an anti-friction bearing, the combination with a retaining member; of an anti-friction roller therein and constantly supported by said retaining member during operation of said bearing; a pendulum member pivoted to the retaining member at the 50 side thereof and adapted to be oscillated by said roller as the latter moves under load; and inter-connecting means between said roller and pendulum member, said means comprising a pin on one of said parts, the 55 other of said parts provided with a substantially elliptical opening so shaped that the pull on said roller by said pendulum will always be in a substantial horizontal direction.

2. In an anti-friction bearing, the combination with a retainer having side and end walls, and an open bottom portion, the upper edges of said side walls being extended inwardly toward each other in overhanging relation; of pendulum members pivotally mounted on said side walls and limited in their pivotal movement by said overhanging portions, said pendulum members being provided with recesses opening toward the free ends thereof; an anti-friction element 70 provided with projections disposed in the recesses of said pendulum members; and a bearing member closing the open bottom of said retainer and providing a bearing surface upon which said element travels.

3. In an anti-friction bearing, the combination with a mounting having a horizontally disposed bearing surface; of a member pivotally connected with said mounting at one of its ends to swing about a fixed axis and normally urged to a vertical position; an anti-friction roller adapted to move to and fro on said bearing surface; and inter-connecting means between said anti-friction roller and said member, said means including contacting surfaces on said member and said roller operating upon movement of said roller to either side of central position to displace said member from normal vertical position, said surfaces being shaped to effect 95 returning force upon said roller by said member in a direction substantially parallel with the line generated by the center of said roller at all points during the movement of said roller.

4. In an anti-friction bearing, the combination with a mounting having a rectilineal bearing surface; of a member pivotally supported in said mounting to swing about a fixed axis and normally urged toward central position substantially at right angles with respect to said bearing surface; an anti-friction roller arranged to travel on said bearing surface; and means in the form of inter-engaging members on said roller and said member for displacing said member from its central position upon movement of said roller to either side of central position on said bearing surface, said inter-engaging members having surfaces so shaped that the line of contact therebetween throughout operation of said roller to either side of central position is substantially normal to the line generated by the center of said roller during its movement to either side of central position on said bearing surface.

5. In an anti-friction bearing, the combination with a retainer having a horizontally disposed bearing surface; of an anti-friction member mounted on said bearing surface and adapted to move to the fro thereon; a centering member swingably connected with said mounting at one end and normally

urged to vertical central position; and inter-connecting means between said members, said means comprising a projection on one of said members, and a vertically disposed 5 substantially elliptical opening in the other of said members, the walls of said opening co-operating with said projection to urge

said anti-friction member to and maintain the same in central position with reference to said retainer.

In witness that I claim the foregoing I have hereunto subscribed my name this 6th day of February 1924.

STACY B. HASELTINE.
